EDMUND BROWN, OF BURLINGTON, VERMONT, ASSIGNOR TO HIMSELF
AND ARTEMUS PROUTY, OF SAME PLACE.

Letters Patent No. 96,195, dated October 26, 1869.

IMPROVEMENT IN BOOTS AND SHOES.

The Schedule referred to in these Letters Patent and making part of the same.

To all whom it may concern:

Be it known that I, EDMUND BROWN, of Burlington, in the county of Chittenden, and State of Vermont, have invented a new and useful Improvement in Boots and Shoes; and I do hereby declare that the following is a full, clear, and exact description thereof, which will enable others skilled in the art to make and use the same, reference being had to the accompanying drawing, forming part of this specification, in which—

Figure 1 represents a plan or top view of a gaiter-boot provided with my improvement.

Figure 2 is a vertical longitudinal section of the same, taken on the plane of the line $x x$, fig. 1.

Similar letters of reference indicate corresponding parts.

This invention relates to a new device for lining the edges of the openings of lace shoes and boots, and has for its object to facilitate the fastening of the two flaps or folds, so that the tedious lacing or buttoning heretofore required can be dispensed with.

The invention consists in applying a metallic or other suitable frame to the edges of the opening, whereby the same is made so stiff, that with but one or two clasps or buckles, the shoe can be closed.

A, in the drawing, represents the upper of a boot or shoe, which is, in front or on the side, provided with a slot or opening, which has to be closed when the shoe is put on. The edges of this opening are lined with a metal or other frame, B, which consists of three bars or plates, $a a$ and b . The two plates a are secured to the sides of the slot, near the lower end of the same, and are, by rivets or pins c , connected with the short plate b that is put across the slot opposite and near the lower end of the same.

The plates $a a$ reach, if in front, only to the instep, as in fig. 2, and will, for slippers or low shoes, be sufficient.

For bootees or gaiters there may be another pair of plates, $e e$, provided, which reach from the upper part of the instep to the upper part of the leg, leaving the instep itself without any stiffening.

For still higher boots, a third and fourth pair of plates may be provided.

The plates a and e may be made of metal, as aforesaid, or of whalebone, rubber, or other suitable material, and are either sewed into the leather or otherwise applied under, within, or above the same.

They stiffen the edges of the slot, and cause thereby the said edges to meet flush, when they are held together at any one point. Thus, one fastening-strap, buckle, or clasp f , will be sufficient for each pair of such plates, and will thereby serve to hold the slot closed.

The tedious lacing, buttoning, or other fastening, heretofore used on such boots or shoes, is thus entirely overcome.

I am aware that hinged stiffening-bars have heretofore been applied to the side seams of boots, but this I do not claim.

Having thus described my invention,

What I claim as new, and desire to secure by Letters Patent, is—

1. The stiffening-frame B, composed of the bars or plates $a a b$, when arranged on a gaiter-boot or shoe, as herein described, for the purpose specified.

2. The combination of the plates $e e$ with the frame B, having the bars $a a b$, all arranged as herein described, to be applied to a gaiter-boot or shoe, leaving the instep elastic, for the purpose specified.

EDMUND BROWN.
